DESIGN FOR A SLIP

Ralph Schiller, New York, N. Y.

Application September 9, 1938, Serial No. 79,809

Term of patent 3½ years

To all whom it may concern:

Be it known that I, Ralph Schiller, a citizen of the United States, with residence in the county of New York, city and State of New York, and post office address at No. 1 East 28th Street, county of New York, city and State of New York, have invented a new, original, and ornamental Design for a Slip, of which the following is a specification, reference being had to the accompanying drawing, forming part thereof, in which,

I claim:

The ornamental design for a slip, as shown and described.

RALPH SCHILLER.
